UNITED STATES PATENT OFFICE

2,616,402

HEATING APPARATUS

Edmond H. Haugen, Birmingham, Mich., assignor
to The Timken-Detroit Axle Company, Detroit,
Mich., a corporation of Ohio

Application May 16, 1949, Serial No. 93,528

4 Claims. (Cl. 122—156)

1

This invention relates to heating apparatus and more particularly to a special boiler construction which is adaptable for heating systems in small housing units.

The heating apparatus of the invention essentially comprises a boiler construction wherein the interior of boiler is separated into lower and upper primary and secondary heat exchange chambers wherein the products of combustion of the liquid fuel burner are intimately associated with the boiler walls for efficient heat exchange with the water column backing the walls, and associated baffle and cover constructions rendering the interior of the boiler which has no openings in its sides accessible from the top.

It is a major object of my invention to provide a novel fabricated boiler construction wherein lower and upper primary and secondary heat exchange chambers backed by a water column are separated by a restricted throat and the internal walls of the boiler are smooth and substantially uninterrupted for non-turbulent passage therethrough of the hot products of combustion arising from the fluid fuel burner.

It is a further object of the invention to provide a novel fabricated boiler construction wherein inner sheet metal members defining the primary and secondary heat exchange chambers and an outer sheet metal shell are welded together to enclose the water space, the smooth internal walls of the boiler providing a continuous path for flow of the hot products of combustion therethrough before escaping through the flue outlet.

It is a further object of the invention to provide a novel top cover and an associated baffle construction for a boiler which has no side openings and has its bottom closed by a hearth supporting a fluid fuel burner, the cover affording access to the interior of the boiler from above and the baffle providing flow direction of the products of combustion.

It is the further object of my invention to provide a novel heating apparatus wherein a combined expansion tank and domestic hot water heater is mounted in novel association with such a boiler.

A further object of the invention is to provide a novel heating apparatus wherein a fabricated boiler and an expansion tank are mounted within the same casing and wherein is provided a novel top cover construction for the boiler affording access to the boiler from above and through the space between the boiler and the expansion tank.

Further objects of the invention will presently

appear as the description proceeds in connection with the appended claims and the annexed drawings wherein:

Figure 1 is a section substantially on line 1—1 of Figure 2 illustrating a heater having a novel boiler and top cover construction according to a preferred embodiment of the invention;

Figure 2 is a top plan view of the heater of Figure 1 with the cover removed on one side of a center line to illustrate the top of the boiler unit;

Figure 3 is a section on line 3—3 of Figure 2 illustrating the boiler and cover construction particularly at the smoke outlet;

Figure 4 is a bottom plan view of the dome baffle and cover plate assembly;

Figure 5 is a front elevation of the dome baffle and cover plate assembly of Figure 4;

Figure 6 is a fragmentary section illustrating a combined boiler and expansion tank apparatus according to a further embodiment of the invention;

Figure 7 is a section substantially on line 7—7 of Figure 6 illustrating further the top cover construction of the boiler in this embodiment of the invention; and

Figure 8 is a fragmentary section illustrating the manner in which the boiler may be attached to a cement hearth.

With reference to Figures 1 through 5, a boiler assembly indicated at 11 is mounted within a sheet metal casing 12 which has a removable top cover assembly 13 that fits with a friction fit on upper rim 14 of the casing. Insulation 15 occupies the space between the casing and the boiler.

The boiler shell, which is made as a separate sub-assembly, comprises an outer cylindrical member 16 having a smooth inside wall and no side openings. The boiler shell further comprises two vertically spaced cylindrical members 17 and 18 which may be of the same diameter, but preferably the upper shell is smaller in diameter to insure more intimate scouring of its inner wall by the outgoing hot combustion gases. Cylinders 17 and 18 are concentric and at their adjacent ends the top of cylinder 17 is provided with a flat annular end wall 19 and the lower end of cylinder 18 is provided with a flat annular end wall 21. The central circular aligned apertures in annular walls 19 and 21 are of the same size, and a relatively short cylindrical member 22 is mounted in these apertures interconnecting annular walls 19 and 21 and preferably projecting a short distance into the interior of member

18 for a purpose to be described. End walls 19 and 21 are welded about their outer peripheries to the adjacent edges of cylinders 17 and 18 respectively, and at the apertures in end walls 19 and 21 they are welded to the outer periphery of cylinder 22, whereby the whole is an integral unit wherein cylinder 22 provides a restricted throat between the lower primary combustion chamber within member 17 and the upper secondary combustion chamber within member 18. These welded joints are fluid tight.

As illustrated in Figure 1, the lower end of member 17 terminates short of the lower end of member 16, and a narrow flat annulus 23 bridges the space between the lower ends of members 16 and 17, preferably being welded to both of them all along its peripheries so as to form a fluid tight bottom wall for the water space of the boiler.

Similarly, a sheet metal annulus 24 is welded or otherwise permanently secured to provide a water tight top wall between the upper ends of members 16 and 18, annulus 24 being disposed a small distance below the upper ends of these members in order that the seating of the cover will not be disturbed as will appear.

This fabricated boiler sub-assembly is thus made up of a number of sheet metal, preferably fire resistant sheet steel about one fourth of an inch thick, elements which are readily formed and welded together in water relation to provide a boiler unit that is open at both top and bottom and divided into a larger lower primary combustion chamber and a smaller upper secondary combustion chamber. The use of thin metal walls in such a boiler is novel in concept in this field because most boilers hitherto have been made from heavy iron and like castings, but I have found this sheet metal construction is unexpectedly advantageous in that the thin metal walls heat up very quickly as soon as the burner is in operation and they speedily transfer heat to the water, whereby this heating apparatus is far more quickly responsive and gets up to house heating temperature much more quickly than most other heater apparatus.

A sheet metal annulus 25 is welded with a gas tight joint about its outer periphery to the lower edge of cylindrical member 16 well below the lower end of member 17. This annulus 25 is adapted to support the hearth assembly which comprises a laminated plate 26 of sheet metal and heat insulation secured as by bolts or the like to annulus 25 so as to be removable from the assembly. An electric motor driven oil burner distributor unit 27 is removably secured as by stud and wing nut assemblies 28 to the bottom of plate 26 and a distributor head 29 driven thereby projects through an aperture in the hearth up into the interior of the boiler within the primary combustion chamber. There the distributor head is surrounded by a shield 30 and an oil atomizing and vaporizing rim 31 substantially the same as that illustrated in United States Letters Patent No. 2,360,891, whereby oil delivered by the distributor head is atomized and mixed with air and ignited by ignitor 32, and the hot products of combustion directed by shield 30 into contact with the inner cylindrical surface of member 17. As illustrated in Figure 1 the cylindrical shield telescopes well up into the interior of cylinder 17 so that no particular dimensions need be observed in assembly.

The entire boiler assembly including the hearth and the motor is supported on suitable legs (not

shown). A separate bottom casing 33 which houses the control mechanism and coil supply means for the burner and through which access may be gained through a suitable door below the level of hearth 26 may be provided but since all of this is not part of the present invention per se, it need not be further described to understand the invention.

Referring now to Figure 2, it will be observed that upper member 18 is not a complete cylinder but is open at one side and formed with spaced parallel outwardly extending walls 34 and 35 defining a flue outlet which as will appear is the outlet for the combustion products. In line with this outlet, outer member 16, see Figure 3, is formed with a suitable recess 36 in its top edge which is located above chamber end wall 21 for receiving the inwardly projecting portion of a smoke outlet hood 37 that is secured to member 16 as by bolts 38 passing through side lugs 39 as shown in Figure 2. This joint between the walls of the smoke hood and cylindrical member 16 includes some gas tight material to prevent the escape of smoke into the room. At its top edge, smoke hood 37 is formed with a flat ridge 41 which lies in the same horizontal plane as the flat top edges of members 16 and 18 so that the cover assembly indicated at 42 will have a continuous seat entirely around the top edge of the boiler which will seal against the escape of smoke except through the smoke outlet hood 37.

The cover assembly 42 comprises a sheet metal disk 43 on the lower surface of which is secured a layer of flexible asbestos or like insulation material 44 adapted to contact the flat top edges of members 16 and 18 and the flat top edge 41 of the smoke hood. The cover seals against the outlet of smoke by its own weight.

Figures 4 and 5 illustrate a dome baffle and cover plate device which is mounted within the secondary combustion chamber in member 18 in concentric relation to the boiler axis and the purpose of which is to direct products of combustion which enter the secondary heat exchange chamber through throat 22 from escaping through the flue outlet before they are intimately directed along the walls of member 18 to extract all heat possible therefrom. This device comprises a sheet metal plate 45 which is preferably an annulus having a circular central opening 46. A baffle member 47 which is preferably a short sheet metal cylinder having the cylindrical side wall thereof removed for a sector opening 48 of about 90 degrees has its upper edge welded to the bottom of plate 45 concentric with aperture 46. This device is placed in the secondary heat exchange chamber with the lower edge of baffle 47 resting on wall 21 and with opening 48 disposed in 180 degrees displaced relation with respect to the smoke hood. Baffle 47 is slightly shorter than the axial height of member 18 so that, when this baffle and plate assembly is disposed in the secondary combustion chamber in concentric relation to the throat 22 and with the lower edge of the baffle resting on annulus 21, the entire baffle assembly will be below the level of cover 42. A radial plate 50 is secured to plate 45 and extends into the smoke outlet space between walls 34 and 35. Throat 22 extends telescopingly well up into the interior of baffle 47 so that the baffle in effect becomes an extension of throat 22.

A deflector sleeve 40, which is preferably a short cylindrical sheet metal member of about the same length as baffle 47, depends from the

cover 42 in radially spaced relation to the baffle but concentric therewith and also extends downwardly well into the interior of throat 22 as illustrated in Figure 1. Sleeve 40 has its upper edge secured as by angles 49 to the lower surface 5 of a circular sheet metal plate 51 which in the assembly rests freely on the upper surface of baffle assembly plate 45 with the deflector sleeve extending freely through opening 46. A pair of studs 56 are threadedly mounted in cover 26 and 10 extend freely through suitable apertures in plate 51 to terminate in large heads 57 at the same level below plate 51. Thus plate 51 is freely movable along these studs toward and away from the cover 42 and the stud heads 57 prevent the plate 51 15 from becoming detached from the cover. Suitable lock nuts 58 are provided for regulating the effective distance of heads 57 from the cover and thereby for regulating the limit of travel of plate 51.

Also mounted on cover 42 are a plurality of studs 59 which have smooth lower shanks 61 extending freely through suitable openings in plate 51 and also through the aperture 46 of plate 45. These studs also have lock nuts 62 whereby they may be axially adjusted. There are three of these studs 59, preferably about 120 degrees apart, and all are on the same radius about the boiler axis. The function of these studs is to center the baffle assembly with respect to the boiler since the circle circumscribing the outer edges of the stud shanks 61 is approximately the same diameter as opening 43, whereby when cover 42 is in place these three studs will not pass through the opening 46 until the baffle assembly is radially shifted into central position with respect to the boiler shell.

Thus it will be seen that when the cover 42 is placed on top of the boiler as in Figure 1, the baffle assembly being already in chamber 18, the deflecting sleeve assembly drops down to rest upon the baffle assembly, and the baffle assembly is centered by studs 59 which will not permit the cover to seat until baffle 47 is concentric with the boiler. The studs 56 permit such upward displacement of 45 the deflector sleeve assembly as may be necessary, and regardless of small manufacturing and dimensional errors the deflector sleeve 40 is always seated concentric with baffle 47 and the throat 22 in the assembly.

A viewing aperture 63 is provided in the center of casing cover 13 which may contain a cemented sight glass for viewing the flame within the lower part of the secondary combustion chamber through apertures 64 in the cover and 65 in 55 the plate 51.

In operation, the hot products of combustion after having travelled upwardly along the walls of the lower primary combustion chamber rise upwardly through throat 22 and discharge into 60 the secondary combustion chamber at 18. The chief purpose of the deflector sleeve 40 is to deflect gases from arising to apertures 65 and 64, plate 51 also forming a deflector baffle in the assembly. Preferably aperture 64 is closed by 65 an openable cap (not shown) so that if any smoke should arise to this level it will not enter the interior of the casing cover. The smoke and other products of combustion discharged into the secondary combustion chamber at 18 are directed by baffle 47 first toward the wall portion of member 18 which is diametrically opposite the smoke outlet. These products of combustion then turn and flow along the interior wall of member 18 in the direction of the arrow of Figure 2 and finally 75

escape between the walls 34 and 35 into the smoke outlet hood 37, thereby insuring maximum length of passage of the hot products of combustion along the chamber walls and hence most efficient heat transfer to the water backing the walls.

When it is desired to inspect the flame it is only necessary to look through opening 63 in the cover and the size and location of openings 64 and 65 is such that it permits the entire flame rim to be visible from the top of the casing. When it is desired to gain access to the bottom of the lower combustion chamber at 17, it is only necessary to remove outer casing cover 13 and cover 42. If necessary the operation may also remove the free baffle assembly, thereby rendering the entire interior of the boiler accessible through the open upper end of member 18 and throat 22.

When it is desired to resume operation of the burner it is only necessary to drop in the baffle assembly substantially in approximately its proper position and then drop the cover 42 onto the top of the boiler assembly, manipulating it until the baffle becomes centered by studs 61, and then replacing casing cover 13.

Suitable water inlet and outlet conduit fittings (not shown) are provided for the water space within the boiler shell for connection with the space heating system of the building in which the apparatus is mounted. The thin-walled boiler which has such a high rate of heat transfer with the water is ideally adapted to a pressure system where a small amount of water is circulated relatively speedily between the boiler and the space-heaters whereby maximum efficiency of operation is obtained. For example such a boiler unit successfully tested has a heating surface of 9.7 square feet and a water capacity of 1.24 cubic feet with a heating capacity of 85 B. t. u. per hour.

In the embodiment of the invention illustrated in Figures 6 and 7, the boiler assembly of the previous embodiment is combined with a combination expansion tank and domestic water heating unit which is mounted in a common casing above the boiler unit and suitably connected to it as will be described.

A plurality of upstanding rigid posts 66 are welded or otherwise secured about the periphery of outer boiler member 16 and to these are secured as by bolt assemblies 67 to corresponding depending legs 68 welded or otherwise suitably secured about a combination expansion tank and domestic heating water tank 69. Tank 69 preferably comprises a cylindrical shell 71 having secured to it upper and lower cup-shaped headers 72 and 73 with their peripheries welded in water-tight relation within the adjacent ends of the shell 71. Preferably the headers 72 and 73 are identical except that the lower header is provided with a drain outlet closed by a plug 74 and the upper header has cemented or otherwise secured to it an external layer of insulation material 75.

Supported within tank 69 as by brackets 76, any number of which may be provided about the interior of the tank, is a coil of copper or like tubing which has terminal couplings 78 extending in fluid tight relation through shell 71. Couplings 78 are suitably connected to the domestic hot water circuit.

An external conduit 79 connects boiler unit 11 80 permanently with tank 69 whereby hot water from the boiler first enters tank 69 before passing to the space heater devices. An outlet fitting 80 in the wall of tank 69 has a branch 81 that feeds hot water to the space heaters (not shown).

and a branch 82 connected to a by-pass return line 83 leading to the fitting 84 at the bottom of the boiler unit. Fitting 84 also has a branch 85 connecting with the return line of the space heater circuit, and fitting 84 preferably contains an internal valve which closes branch 85 except when the circuit pump is in operation to prevent dissipation of hot water into the space heater circuit when it is not desired there. Such a valve per se is disclosed and claimed in the co-pending application of James H. Miller Serial No. 53,269 filed October 7, 1948 to which reference is made for further detail if necessary to understand the present invention.

Casing 12 and the boiler unit and associated burner enclosed thereby are preferably substantially the same as in Figure 1. In place of cover 13, however, there is friction fitted on rim 14 an upright cylindrical casing extension 86 closed at the top by a cover 87. A layer of insulation 88 is provided between casing 86 and the tank 69. The length of legs 68 is such that a considerable space 89 is provided between the top of the boiler unit and the bottom of the expansion tank, and a removable door 90 is provided in the wall of casing extension 86 whereby access may be gained to this space for the purpose of draining tank 69 or removing the boiler cover 91 for access to the interior of boiler 11 through its top.

Cover 91, like cover 42, is a laminated sheet metal and insulation disk adapted to seat by its own weight on top of the boiler. One difference is that the diameter of cover 91 is much smaller in this embodiment wherein it is substantially only little larger than the diameter of cylinder 18 so that it will not interfere with the mounting of casing extension 86 upon the rim.

A radial cover extension 92, as illustrated in Figure 7, is rigidly secured to cover 91 and extends into contact with the inner periphery of casing extension 86 overlying boiler walls 34 and 35 and rim 41 of the smoke hood for insuring that no smoke escapes to the space 89. Two studs 93 project downwardly from cover extension 92 to engage the inner sides of boiler walls 34 and 35 to properly locate the cover on the boiler.

The deflector sleeve assembly and the baffle unit within the secondary chamber 18 are substantially the same as described in the earlier embodiment. Sight aperture 64 in the cover is closed by a hinged cover plate 94.

It will be seen therefore that after removing door 90 there is adequate space for a workman or inspector to gain access to cover 91. A suitable drain cock 95 is provided in the side of tank 69 for drawing off excess water from the system.

Suitable controls are provided (not shown) for insuring that the oil burner is operated whenever either the domestic hot water system or the space heater system demands heat, and the rapidity with which the sheet metal boiler heats the water therein is particularly advantageous in both systems for insuring speedy and efficient operation.

Figure 8 illustrates an alternative permanent hearth construction for boiler unit 11, wherein the bottom edge of the boiler shell is embedded about the periphery, a hearth of refractory cement 95 supported on a steel plate 96.

The invention may be embodied in other specific forms without departing from the spirit or essential characteristics thereof. The present embodiments are therefore to be considered in all respects as illustrative and not restrictive, the

scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. Heating apparatus comprising a boiler shell open at top and bottom and having an intermediate restricted throat between lower primary and upper secondary combustion chambers, said shell having a lateral flue passage therethrough in communication with said upper chamber, a hearth and fuel distributor assembly closing the lower end of said shell, a removable cover assembly closing the upper end of said shell, a tubular baffle assembly of smaller cross-section than said secondary combustion chamber separate from the boiler shell for controlling flow of products of combustion entering said secondary combustion chamber through said throat mounted in said secondary combustion chamber between the cover assembly and said boiler shell, said baffle being laterally apertured opposite said flue passage, and said cover assembly comprising a part mounted across the upper end of said boiler shell and a relatively movable horizontal plate mounted for vertical movement under said part and resting on said baffle in the assembled apparatus.

2. In heating apparatus, an open top and open bottom boiler shell comprising a cylindrical sheet metal outer wall, vertically spaced upper and lower cylindrical sheet metal inner walls surrounded by and spaced from said outer wall and enclosing upper and lower combustion chambers, said cylindrical walls having parallel vertical elements, said lower chamber enclosing wall having a smooth imperforate internal surface of circular cross-section and said upper chamber enclosing wall having a smooth internal surface of circular cross-section interrupted only by a lateral flue outlet and said chambers being substantially unobstructed internally, a hollow cylindrical member of substantially circular cross-section defining a restricted throat between said chambers, transverse walls within the shell connecting the adjacent ends of said inner cylindrical walls to said throat member, and transverse end walls on the shell connecting the upper and lower ends of said outer cylindrical wall to said upper and lower inner cylindrical walls, respectively, to define a vertically continuous water column backing said chambers.

3. In heating apparatus, a boiler shell comprising an upper combustion chamber having a lateral flue outlet aperture and a bottom wall with a throat opening to admit products of combustion, a baffle assembly comprising a tubular baffle member seated upon said bottom wall surrounding said throat opening and having a lateral aperture on the side opposite said flue outlet aperture, an inwardly extending lateral extension on said baffle assembly, a cover assembly seated upon the top of said shell, a deflector sleeve on said cover assembly extending downwardly through said tubular baffle member and into said throat opening, an outwardly extending lateral extension on the upper end of said deflector sleeve resting on said baffle assembly lateral extension when the cover is on the boiler shell, means mounting said sleeve on the cover to permit relative vertical movement therebetween when the cover assembly is placed on the boiler shell, said means also maintaining the cover in assembly

with the sleeve when the cover is removed from the boiler shell, and means on said cover assembly adapted to engage and center the baffle assembly in said chamber when the cover is on the boiler shell.

4. In heating apparatus, a boiler shell having an upwardly open upper combustion chamber formed with an inlet throat in its bottom wall and a flue outlet in a side wall, a tubular baffle member seated on said bottom wall in surrounding relation to said throat and having a lateral outlet opposite said flue outlet, a removable cover assembly extending across the top of said shell, and means on said cover assembly depending within said chamber for engaging and centering 15 said baffle member with said throat.
